UNITED STATES PATENT OFFICE.

PATRICK MULLANE, OF MOLINE, ILLINOIS.

HASP-FASTENER.

SPECIFICATION forming part of Letters Patent No. 607,873, dated July 26, 1898.

Application filed November 28, 1896. Serial No. 613,747. (No model.)

To all whom it may concern:

Be it known that I, PATRICK MULLANE, a citizen of the United States, residing at Moline, in the county of Rock Island and State 5 of Illinois, have invented a certain new and useful Improved Self-Fastening Combination Hasp and Staple, of which the following is a specification.

The object of my improvement is to provide 10 a novel form of hasp and staple which will not become accidentally unfastened, which can be locked with a padlock or other locking device, and which can be made cheaper than other styles of hasp and staple, and in 15 which also the hasp will turn on the staple freely and will readily drop to its place in fastening position.

I accomplish my objects by providing a hasp which is provided with the usual openings, one for securing it permanently to the door and the other to the post for securing it when in the locking position. The latter is an elongated opening, while the former is the simple round opening ordinarily employed. 25 Both openings, unlike the openings in prior hasps, are placed near the top of the hasp, so that the weight of metal in locking position will be below the staple. The staple for permanently securing the hasp is of the ordinary 30 construction. The staple for securing the hasp when it is desired to lock the door is bent at substantially right angles, so that the exposed portion is in practically the same horizontal plane as the door or post to which 35 it is attached. This latter staple may be made by bending an old-style staple or may be made in other forms. By employing a hasp with an elongated opening near its upper edge and combining the same with a bent 40 staple, as explained, the hasp will be brought to a horizontal position before being placed in or removed from locking position.

In the accompanying drawings, forming part of this specification, Figure 1 is an elevation showing my improved hasp and staple practically applied. Fig. 2 is a side elevation thereof. Figs. 3 and 4 are respectively an elevation and side view of another form of staple, and Figs. 5 and 6 show a modified form 50 of hasp.

A represents a door, and B the door-post.

C represents the hasp, which, as shown, is provided with a hole D near its upper edge, through which passes an ordinary form of staple E, which secures the same permanently 55 to the door. An elongated opening F is provided at the other end of the hasp, also near the top thereof, which is adapted to engage with and be secured by the staple G, the construction of which is best shown in Figs. 2, 60 3, and 4. This staple may be the ordinary form of staple, a portion of which is bent at right angles to itself, with the loop portion slightly turned upward, as shown at x, Fig. 2. When the staple is driven, one portion 65 thereof will be in substantially the same plane with the post to which it is attached. In Fig. 3 I have shown the staple formed from a plate and not from the ordinary wire staple. In these figures, H represents the portion which 70 is attached to the door or post by screws or nails, the holes for which are shown in Fig. 3. I represents the portion which lies in practically the same plane with the door or post, and J represents the hole through which a 75 padlock or other sealing device may be passed.

In Figs. 5 and 6 I have shown a form of hasp which is made by bending the upper edge of the hasp into tubular form, as shown 80 at K. By so doing an easy and free movement of the hasp on the staple is permitted and rattling is in a large measure prevented.

It will be observed that by having the weight of the hasp toward its lower edge, 85 which is accomplished by locating the openings near its upper edge, the hasp will by being moved to a horizontal position readily pass over the locking portion of the staple because of the weight of metal below the 90 openings and will tend to remain in its locking position because of such weight, thereby preventing an accidental unloosening.

If desired, a padlock or other sealing device may be passed through the opening in 95 the staple.

I claim—

1. The combination with a hooked locking-staple and an attaching-staple, of a hasp having apertures for said staples near its upper edge so that the weight of metal in locking 100 position is below the staples, and of such

shape that the hasp must be brought to a horizontal position before being placed in or removed from locking position, substantially as set forth.

5 2. The combination with a hooked locking-staple, of a hasp having its upper edge shaped in cylindricical form, and apertures near its upper edge and close to the cylinder formed

thereon for attaching the locking-staples, for the purpose substantially as set forth. 10

This specification signed and witnessed this 23d day of November, 1896.

PATRICK MULLANE.
